(57) **CLAIM**

The ornamental design for a solar rotating hanger, as shown.

DESCRIPTION

The claimed solar rotating hanger is used for hanging baskets. The lower hanger will rotate when the motor in the body receives solar energy.

FIG. 1 is a front elevational view of a solar rotating hanger showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a perspective view thereof;

FIG. 8 is a perspective view thereof with the upper hanger being put in a different position;

FIG. 9 is a perspective view thereof with the upper hanger being put in a further different position; and,

FIG. 10 is a perspective view thereof with the lower hanger rotates to another direction.
